UNITED STATES PATENT OFFICE.

WILLIAM L. DORAN, OF NIAGARA, CANADA.

SUSPENDER-BUCKLE.

SPECIFICATION forming part of Letters Patent No. 527,170, dated October 9, 1894.

Application filed July 12, 1894. Serial No. 517,336. (No model.)

To all whom it may concern:

Be it known that I, WILLIAM L. DORAN, a citizen of the Dominion of Canada, residing at Niagara, in the county of Welland and Province of Ontario, Canada, have invented certain new and useful Improvements in Suspender-Buckles; and I do declare the following to be a full, clear, and exact description of the invention, such as will enable others skilled in the art to which it appertains to make and use the same.

My invention relates to improvements in suspender buckles, and it has for its general object to provide a simple and strong buckle adapted to be securely fixed in position upon a shoulder strap or other part of a pair of suspenders without cutting, indenting, or otherwise injuring the same, and one embodying a clamp adapted to be readily loosened to permit free adjustment of the buckle and also adapted, when in its normal operative position, to serve as a guard to prevent a casual disengagement of the eye of the suspender tabs from the hook of the buckle.

Other objects and advantages of the invention will be fully understood from the following description and claims when taken in connection with the annexed drawings, in which—

Figure 1, is a perspective view illustrating my improved buckle as fixed in position upon a suspender strap. Fig. 2, is a vertical section of the same. Fig. 3, is a detail perspective view of the frame of my improved buckle, and Fig. 4, is a similar view of the clamp.

Referring by letter to said drawings:—A, indicates the frame of my improved buckle, and B, indicates the clamp which is designed and adapted to fix the frame in position upon a suspender strap as will be presently described. The said frame A, is preferably made of wire; and in forming the same I first bend a piece of wire upon itself at a point midway of its length and shape the same so as to form the hook a, and the shank b, as shown. I then carry the branches of the wire laterally in opposite directions to form the lower side c, of the frame and then upwardly to form the ends d, of the same, after which I bend the said branches downwardly against the frame ends d, to form the bearings e, and then inwardly to form the upper side f, of the

frame. The ends of the wire which form the upper side f, of the frame preferably rest in a plane in front of the ends d, and they are 55 connected for the sake of strength by a barrel as g.

The clamp B, of the buckle is also preferably made of wire, and in forming the same I first bend the piece of wire to form the 60 tongue or finger h, or lower side of the clamp and the ends i. I then pass the branches of the wire through the bearings e, of the frame A, and bend them downwardly and inwardly as shown at j, and carry the ends of the same 65 inwardly toward each other and surround them by a barrel to form the upper side k, of the clamp. When the clamp B, is in the position shown in Fig. 1, this upper side k, rests above and slightly in rear of the plane of the 70 upper side f, of the frame A, and serves to securely clamp the suspender strap which is arranged as shown and prevent movement of the buckle thereon, while when the tongue h, or lower side of the clamp is raised to a position at right angles to the frame, the upper side k, of the clamp, will be caused to assume a position above and slightly in front of the 75 upper side f, of the frame A, so as to permit of the suspender strap C, moving freely between said sides f, k, when the buckle is adjusted. When the lower side of tongue h, of the clamp is lowered to the position shown in Fig. 1, the upper side k, of said clamp will spring over the strap and upper side f, of the 80 frame into the position above and slightly in rear of the plane of the said side f, so as to securely clamp the strap and hold the lower side or tongue h, in the position shown in Fig. 1, in order to enable it to prevent the eye l, 85 of the tabs from being casually disengaged from the hook a. By reason of the upper side k, of the clamp springing into position as above described when the tongue h, is swung into its operative position, said tongue 90 will be securely held against casual movement. The tongue however is adapted to serve as a lever and by pressing the same outwardly, the upper side k, may be readily raised to a position above and in front of the 95 side f, of frame, to permit adjustment of the buckle on the strap C.

It will be seen from the foregoing that the clamp B, of my improved buckle is adapted

to securely fix the buckle in position upon a web strap, without cutting, indenting, tearing, or otherwise injuring the same, and that my buckle is therefore superior to those which are necessarily provided with teeth or barbs to engage the strap. It will also be noticed that by reason of the peculiar construction of my buckle, the clamp B, may be raised and the buckle adjusted on the strap without the necessity of disconnecting the tab eye *l*, from the hook *a*, which is a desideratum.

I have described my improved buckle as formed of wire as such material is best suited to the purpose. I do not desire however to be understood as confining myself to making the buckle of wire as it may be made of any other suitable material.

Having described my invention, what I claim is—

1. A buckle frame made from a piece of wire and composed of the lower side *c*, and upper side *f*, connected by two ends *d*, and having the bearings *e*, above the upper side, in combination with a clamp made from a

piece of wire and pivoted in the bearings *e* 25 of the frame and composed of a lower side *h*, and an upper side *k*, connected by ends *i*, and having the portions *j*, between the upper side *k*, and ends *i*, substantially as specified.

2. In a buckle, the combination with a frame 30 made from a piece of wire and composed of the lower side *c*, and upper side *f*, connected by the two ends *d*, and having the hook depending from the lower side and bearings *e*, above the upper side; of a clamp made from 35 a single piece of wire and composed of the lower side *h*, shaped to form a tongue or finger and an upper side *k*, connected by ends *i*, and having the portions *j*, journaled in the bearings *e*, of the frame, substantially as 40 specified.

In testimony whereof I affix my signature in presence of two witnesses.

WILLIAM L. DORAN.
